UNITED STATES PATENT OFFICE.

FERDINAND S. BARTRAM, OF NEW YORK, N. Y.

FOUNTAIN PEN AND HOLDER.

SPECIFICATION forming part of Letters Patent No. 380,014, dated March 27, 1888.

Application filed January 20, 1887. Serial No. 224,960. (No model.)

To all whom it may concern:

Be it known that I, FERDINAND S. BARTRAM, a citizen of the United States, and a resident of New York, in the county of New 5 York and State of New York, have invented certain new and useful Improvements in Fountain-Pens and Fountain-Holders, of which the following is a specification.

My invention pertains to that class of fountain-pens having a tubular or hollow case closed at its upper end, which may be charged with ink at its lower or open end, or at a joint in said case near its lower end, providing for the admission of air only at the lower or open end 15 of said tubular case.

The accompanying drawings form a part of this specification, and represent what I consider the best means of carrying out the invention.

20 Figure 1 shows the pen complete in all its parts. Fig. 2 is an external lateral view of the ink-conductor *b* when used without the regulator *c*. Fig. 3 is a lateral view of the ink-conductor *b* when used without the regulator 25 *c*, or vent *g*, or rests *e e*. Fig. 4 is a bisected longitudinal view of the ink-conductor *b*, showing the central perforation, *h*, for the conveyance of ink through the body of the same, and also one or more capillary channels, which may 30 be constructed upon the inner surfaces of the lips *ff*, to which further reference will be made. Fig. 5 is a detached lateral view of the regulator. Fig. 6 is a transverse view of the ink-conductor *b* in Fig. 1. Fig. 7 represents the 35 cap or cover, which is adjusted upon the shoulders at either end of the case or tube and protects the pen when carried in the pocket.

Similar letters of reference indicate corresponding parts in all the figures where they 40 occur.

Letter *a* indicates the case and reservoir, which may be constructed of hard rubber or other analogous material, of tubular form, and closed at its upper end, as previously described. 45 It may be integral in form, or may have a joint or section connected by screw-threads near its lower end, for purposes of refilling, &c. When the case is composed of a single tube, the reservoir is charged at the open end by without 50 drawing the pen and ink-conductor together or separately.

Letter *b* represents the ink-conductor, which

is constructed of hard rubber or other suitable material, the backward portion of which is a cylindrical plug conformed to and held by friction within the case or tube, and perforated longitudinally at or near its center and about midway of its length, for the purpose of conducting ink from the fount or reservoir. The forward or opposite end of this conductor is 60 reduced, or partially pointed and slightly flattened upon two sides to conform it to the shape of a pen, when it is bisected from said point through the flattened sides sufficiently to intersect the perforation *h* and receive a pen (between its two equally or nearly equally projecting lips thus formed) nearly its entire length. When the pen is inserted between these lips (being prevented from moving side- 65 wise by the diameter of the tube or case) and 70 abuts against the central perforation, *h*, the column of ink is divided nearly equally and flows down simultaneously upon both sides of the pen to or near its point.

Letter *c* is the regulator, which is adjustable longitudinally, and serves the purposes of a ventilator and partial or entire cut-off of air to or ink from the fount through either or both the perforations *g* and *h*. It is constructed of a small parallel rod, of hard rubber or other 80 material, inserted loosely within and through the orifice *g* in the body of the conductor above the pen. To the forward end of this rod is affixed a short upright lever or button, *c'*, by which it may be moved forward or backward 85 to regulate the ingress of air to or egress of ink from the fount through the perforations *g* and *h*. The backward end of this rod or regulator is enlarged conically, in order that when the rod is drawn forward by the button *c'* the enlargement will be drawn into and close partially or entirely the perforation *g*. To this 90 enlargement is attached a short perpendicular bar, pending downward, to which is secured a similar conical plug, which is made, by the 95 same operation, to close in like manner the perforation *h*, so that the pen may be carried in any position without danger of leaking. I attach much importance to this feature of the invention, as either of the cones may be arranged at different points of contact with the two orifices *g* and *h*, and by the same movement close the upper one partially and the other entirely, or vice versa, thus adapting the 100

flow to any of the varying requirements or conditions which air and ink may combine to produce.

Letter *d*, Fig. 1, represents an ordinary steel 5 metal or gold pen in position.

Letters *e e* are two braces or supports upon either or both surfaces of the lips of the ink-conductor, formed by bifurcating the outer surfaces of the same and turning their forks 10 outward or attaching them in any substantial manner, with their ends resting within and against the inner surface of the tube or case, and designed to maintain a pressure and prevent the lips of the ink-conductor from deflecting from their normal position with reference to the pen.

Letters *ff* are the two lips referred to, which are formed integral with the body of the conductor, but do not extend within nor permit 20 the pen to extend into the reservoir.

Letter *g* is the upper perforation above the pen, through which the regulator passes loosely and sufficiently to admit air around it to the fount. It extends through the conductor to the 25 button *c'*, where it opens upward through a narrow slot, in which the lever moves, or to which the button is attached. Underneath this button or lever a small orifice extends downward from the perforation *g* through the 30 upper lip to the pen, by which means any surplus ink may be drained to the pen when in action.

Letter *h* is a simple perforation, of the required diameter, extending through the central portion of the body of the conductor, and 35 may, like the perforation *g*, have its backward orifice enlarged to correspond with and receive the stop or cone affixed to the regulator-bar, making the connections air-tight when 40 necessary.

The whole is exceedingly simple, practical, and durable; but a cheaper construction may be secured by the use of the conductor, Fig. 3, without the stop or vent perforation or rests 45 hereinbefore described. By filling an ordinary tube with ink, leaving sufficient space to adjust this conductor loosely within the same, and inserting a common pen between its lips, the whole will serve all the ordinary purposes 50 of a fountain-pen.

The operation of this construction requires simply that the fount be charged with ink at the open end, or, when the regulator is used, at the jointed screw-section of the case. When 55 the parts are in proper position, as before described, the pen is ready for instant service.

It is evident that various changes may be made in the form and arrangement of the several herein-described parts without departing 60 from the spirit and scope of my invention; hence I do not wish to limit myself to the rigid or precise construction herein set forth.

The lips of the conductor may be formed longer or shorter, narrower or wider, to adapt 65 them to pens of almost any length, shape, or thickness, and it may be used with or without the rests, or with one upon the upper or un-

der side alone. The body of that portion of the conductor retained within the case may be longer or shorter, and of varying circumference to adapt it to any tube used for the purpose. When used without the regulator, the vent-perforation may or may not be omitted, and when omitted sufficient air will pass upward between the inner surface of the tube and 75 outer surface of the conductor for ordinary purposes. The inner surfaces of the lips of the conductor may be flat, concaved, convexed, grooved, or scarified, as shown in Fig. 4, to facilitate, if necessary, the flow from the points 80 of contact with the pen. The conductor may be constructed of solid, tubular, or bisected material, and the parts joined subsequently, as a means of facilitating and cheapening its construction. 85

I have hereinbefore described this invention with reference to its adaptation to the use of ordinary pens or writing-nibs inserted between the lips of the conductor. I now desire to explain the manner of its use for a similar 90 purpose without the employment of such pens or any pen, and when adapted to such capacities I have termed it a "styloid." When the fount is charged with ink and the conductor inserted without a pen, the lips of the conductor, which may preferably be slightly bent inward at the point, act in conjunction, and serve all the purposes of a pen, the ink being conveyed down upon both inner surfaces, and held between them until released by their 100 elastic combined action, produced by pressing the points of either upon the paper or any other substance, as in the ordinary act of writing. This is one of the most important features of the invention. Again, when held in 105 such manner that both lips may rest upon the paper equally and be moved in any direction, it operates as a perfect ruling device, making a free, continuous, and uniform line as long as any ink remains in the reservoir. Its value 110 for such uses is incalculable. It may be adapted to various other purposes, such as a fount for the application of mucilage, or as a marking device for commercial uses, thus dispensing with the antiquated pot and brush, 115 or a brush, or sponge, or other absorbent may be inserted between the lips of the conductor for this or other purposes where a limited, continuous, or intermittent supply of almost 120 any fluid may be required to be conveyed or transmitted to locations inaccessible to or by other methods in medical, surgical, or other practices or uses.

Either or both the perforations *g* and *h* of the conductor may be employed for any of its 125 purposes, and the stop, vent, or rests, hereinbefore described—either or all—may be used or omitted. The points of the lips of the conductor may be formed for writing, sketching, shading, drawing, or ruling any required 130 width, and when worn are easily replaced, or may be pointed or mounted with or constructed of any durable material. The points or flattened edges of the lips of the conductor may

be serrated partially by one or more transverse incisions without detriment to their various functions, when it operates as a perfect shading pen.

5 I claim as my invention—

1. In a fountain-pen, an ink-conductor consisting of a plug, of hard rubber or other suitable material, inserted or adjusted partially within the open end of a tube-case or reservoir and independent of the outer section thereof, said plug being provided with a longitudinal perforation communicating with the reservoir and pen, and having its lower or exposed end reduced, tapered, or pointed, and 15 also bisected longitudinally from its pointed end backward to form two projecting lips or arms a portion of its length, between which lips or arms a pen may be inserted, said pen being partly within the case, but wholly without the reservoir, for the purpose of controlling 20 the flow of ink to the pen by intersecting the perforation in said plug and dividing and conducting the flow simultaneously down both upper and under surfaces of the pen from its heel to or near the point.
2. In a fountain-pen, a regulator or stop consisting of a movable and adjustable horizontal bar arranged within a perforated feed plug or bar communicating with the reservoir and pen, 30 having its backward end enlarged or convexed to form a stop, designed to open, graduate, or close said perforation, and thereby regulate or control the ingress of air to and the egress of ink from the reservoir or tube to the pen.
3. In a fountain-pen, a regulator or stop consisting of a movable and adjustable horizontal bar arranged within a cylindrical feed plug or tube fixed within the open end of the case or reservoir, and communicating with the reservoir and pen by means of one or more longitudinal perforations, said bar having one or 40 more enlargements or convexed stops formed or affixed to its base, adjusted and fitted to

enter a corresponding seat or seats within said perforations, and designed to equalize and control by proper adjustment the concurrent natural forces of the air and ink for the successful operation of the fountain and pen.

4. In a fountain-pen, one or more braces or rests upon a feeding tube or bar, consisting of one or more prongs formed by bifurcating the surface of said bar, or affixing them to said bar, and having their detached ends formed to rest within and against the inner surface of the tube or case, for the purpose of supporting the bar within the tube and strengthening the points of said bar or feeding device.

5. The fountain-pen herein described, consisting of the combination of the case *a* and pen *d* with the ink-conductor *b*, having the regulator *c*, all constructed and arranged for joint operation, substantially as and for the purposes specified.

6. For the reception, retention, and continuous or intermittent distribution of ink or other fluids, a fountain-holder or reservoir, in combination with a conductor inserted or adjusted within the open end of said reservoir, being perforated longitudinally from its backward end part way of its length, and having its forward end reduced by tapering or partially pointing the same, said pointed end being bisected longitudinally and centrally, or nearly equally, to form two lips, one being over, above, or opposite the other, and which inner surfaces face each other, the space between said lips communicating with the said perforation, and all constructed and arranged for joint operation, substantially as hereinbefore described.

Signed at New York city, in the county of New York and State of New York, this 19th day of January, A. D. 1887.
